UNITED STATES PATENT OFFICE.

THOMAS B. HUGHES, WILLIAM J. DAVIS, AND DAVID DANIEL HUGHES, OF GRANITE CITY, ILLINOIS.

FEEDING MECHANISM FOR PLATES AND THE LIKE.

1,383,304.

Specification of Letters Patent.

Patented July 5, 1921.

Application filed April 27, 1920. Serial No. 376,935.

To all whom it may concern:

Be it known that we, THOMAS B. HUGHES, WILLIAM J. DAVIS, and DAVID D. HUGHES, citizens of the United States, residing at Granite City, in the county of Madison and State of Illinois, have invented certain new and useful Improvements in Feeding Mechanism for Plates and the like, of which the following is a specification.

10. This invention relates to feeding mechanism for plates and the like.

The object of the invention is to provide simple and efficient mechanism by means of which tin or other plates may be mechanically fed to a cold-roll or other mechanism.

Another object is to so construct such a machine that the plates will be removed by suction, one at a time and carried to the receiving mechanism of a working machine.

20. Another object is to construct such a machine so that the operation will be entirely mechanical and maintained continuously yet is at all times within the control of the operator.

25. With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30. In the accompanying drawing:—

Figure 1 represents a top plan view of the mechanism constituting this invention.

Fig. 2 is a side elevation thereof.

Fig. 3 is a longitudinal vertical section.

40. Fig. 4 is a detail horizontal section with parts broken out of the plate engaging funnels and their adjacent parts.

Fig. 5 is a detail longitudinal section of the funnels; and

45. Fig. 6 is a detail longitudinal section taken on the line 6—6 of Fig. 1.

In the embodiment illustrated the mechanism constituting this invention is mounted on a base member 1 which preferably comprises two sides connected by a top 2 to form a hollow structure. Mounted on the top 2

are parallel track rails 3. on which a car 4 is mounted to travel. This car 4 has the bottom 5 thereof made comparatively low and is supported by front and rear wheels 6.

A frame is also supported on the base member 1 and is composed of uprights 9 and cross bars 10. This frame is so constructed as to permit the car 4 to have movement therein in its path of travel along the track 3.

Shafts 11, 12, 13, and 14 are journaled in the uprights 9 and cross bars 10 and extend transversely of the frame in a plane above that occupied by the floor or bottom 5 of the car 4. These several shafts have rolls 15 and 16 carried thereby at points spaced apart and over which are mounted to travel belts or conveyer webs 17 and 18 which move in the direction indicated by the arrow *a* in Fig. 3.

A drive shaft 19 extends transversely between the side members of base 1 and has fixed thereto a drive pulley 20 around which is passed a belt 21, which extends to any suitable source of motive power and transmits revoluble movement to the drive shaft 19. A sprocket 22 is secured on the drive shaft 19 and revolves therewith and a sprocket chain 23 passes over the wheel 22 and a sprocket gear 24 mounted on shaft 11, whereby movement is transmitted through said shaft 11 to the conveying webs or belts 17 and 18.

A tubular operating shaft 28 is mounted to rotate on a hollow shaft 30 arranged transversely of the machine in rear of the plane occupied by the shaft 13 and has fixed thereto a step pulley 26 over which passes a belt 27. This belt 27 also passes over another step pulley 25 secured to shaft 13 to transmit motion from shaft 13 to shaft 28, for a purpose presently to be described. The step pulleys 25 and 26 have the steps thereof tapered in opposite directions so that the speed of rotation of shaft 28 may be increased or decreased with respect to the speed of travel of the shaft 13 to meet various conditions of operations.

The shaft 28 has hollow arms 29 extending at right angles therefrom at diametrically opposite points, the hollow shaft 30 having an opening 31 in the rear wall there-

of which is designed to register with one or the other of the arms 29 during the turning of shaft 28, as is shown clearly in Fig. 4. Funnels 32 and 33 having cylindrical necks 34 are mounted for sliding movement on the arms 29, said funnels being connected by rods 35 so that they will move in unison. The weight of the connected funnels causes them to slide on the arms 29 when the shaft 28 is rotated so that one funnel will be positioned for engagement with one of the plates 37 which are mounted upon the floor 5 of car 4, so that as the connected funnels rotate, the foremost plate which is held by suction against the funnel will be carried over and delivered on to the conveyer webs 17 and 18 by which the plates will be carried to the proper point and fed to the rolling or other working machine.

The hollow shaft 30 is connected with a pipe 36 for producing vacuum within the shaft 30 which communicates with the shaft arm 29, or rather with one of them so that suction will be alternately produced in the funnels 32 and 33. It will thus be seen that when the machine is in operation motion will be transmitted from the driving shaft 19 to the hollow shaft 28 which rotates carrying with it the connected funnels 32 and 33. This rotation of the funnels causes them to slide on the arms 29 and one of them which is in communication with the hollow shaft 30 engages one of the plates 37 and carries it over and deposits it on the belts 17 and 18, the plate being released when the suction in the funnel carrying it is broken and this occurs when said funnel passes out of register with the opening 31 in the tube or hollow shaft 30.

To maintain the car 4 always at a position in which the funnel, which is in communication with shaft 30 will contact with and take from the car one of the plates 37, it is essential that some means be provided to move the car along the track 3 a predetermined distance with each half rotation of shaft 28 and consequently this movement must be judged by the rotation of said shaft 28. To accomplish the object above set forth, sprockets 42 and 43 are mounted on the shafts 44 and 45 and over which passes a sprocket chain 46. This chain 46 has a plurality of spaced lugs 47 mounted to project from the outer face thereof and when the parts are in the position indicated in the several views, and motion is transmitted to this sprocket chain 46, one of the lugs 47 will engage with the front axle of the car and move the car forward. It is desired that a step-by-step movement be transmitted to this sprocket chain 46, so that the car will be moved forward a distance equal to the thickness of one of the plates upon each half revolution of the shaft 28.

A ratchet wheel 48 is mounted on a trans-

versely disposed shaft 49 journaled in brackets carried by the sides of the base 1. An arm 50 is pivoted on the shaft 49 for swinging movement with respect to the ratchet wheel 48 and is provided with a dog 51 to engage the teeth of the ratchet wheel. A bevel gear 52 is secured on the shaft 49 to be revolved as movement is transmitted to the ratchet wheel by the swinging of the lever 50. A shaft 53 is mounted to extend at right angles to shaft 49 and carries a beveled gear 54 which meshes with the gear 52. A worm 55 is secured to the shaft 53 and meshes with a worm wheel 56 fixed to the shaft 44, whereby the turning movement of the ratchet wheel 48 will be transmitted to the shaft 44 and thereby operate the chain 46.

A crank disk 57 is secured to one end of the shaft 13 and a link 58 connects it with the lever 50, said lever having a plurality of openings 59 to provide for the adjustable connection of the link 58 therewith. This connection of link 58 with lever 50 regulates the extent of swinging movement of said lever to vary the distance which the ratchet wheel 48 will be moved forward by the engagement of the dog 51 therewith.

Any suitable mechanism may be provided for raising and lowering sprocket chain 46 to throw out of operation the chain 46 and its connected parts and yet permit an operation of the parts which are driven by the belt 21. As this mechanism constitutes no part of this invention, it is not deemed necessary to describe it.

From the foregoing it will be seen that we have provided a mechanism by which tin-plates or plates of any other material may be fed to a working mechanism without manual handling, and that the plates are taken one by one from a common carrier or holder and each is operated upon separately and is fed at just the proper points; further it is evident that the machine is automatic in its operation, each part being accompanied by a mechanical movement and the several parts thereof may be regulated and adjusted to accommodate varying operating conditions.

From the foregoing description, taken in connection with the accompanying drawings, the advantages of the construction and the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

What is claimed is:—

1. A plate handling machine comprising 130

means for supporting a stack of plates, and rotatably and slidably mounted oppositely disposed connected suction funnels for alternately engaging a plate to convey it to a 5 place of deposit.

2. A feeding mechanism for plates including a plate carrier, funnels rotatably mounted on a common axis to successively pick the plates from the carrier, each funnel being 10 radially movable inwardly prior to releasing a plate and being radially movable out-

wardly, after having released the plates substantially as described.

In testimony whereof we affix our signatures in presence of two witnesses.

THOMAS B. HUGHES.

WILLIAM J. DAVIS.

DAVID DANIEL HUGHES.
